DEVICE FOR DISPENSING AND MIXING
PAINT AND THE LIKE

Nicholas Grubelis, Great Neck, N. Y.

Application March 19, 1935, Serial No. 11,893
Renewed February 8, 1939

25 Claims. (Cl. 221—103)

This invention relates to devices for dispensing and mixing paints, etc.

At the present time, paints for use in shops where re-painting and re-touching is done are mixed from several different containers with the aid of mixing utensils and in accordance with predetermined formulae.

The paint manufacturer at the present time provides standard colors in quart containers. 10 When it is desired to attain a quantity of mixed paint, a formula is consulted and with the aid of the mentioned utensils, two, three or more of the standard colors are mixed to attain the desired blend.

15 As can readily be understood, the opened containers of standard paint being exposed to atmosphere, a certain amount of dehydration occurs, and thereafter, paint in such a used container would be more heavily pigmented per fluid ounce. This prevents successfully using the same formula at a later time for matching the original paint, only the experience of the person doing the mixing serving to ultimately and after great effort, attain an exact match.

20 Further, the formulae supplied are for the purpose of attaining a mixture of one quart, but should, for instance, ten or twelve ounces of mixed paint be desired, the mathematical calculations involved would ordinarily be too difficult 25 for the person doing the mixing and the mentioned utensils could not be employed with the same facility.

The present invention therefore contemplates the provision of means whereby any desired quantity of mixed paint may be attained with minimum effort and with great facility.

30 The invention also contemplates the provision of means whereby standard paint containers may be dispensed from at different periods of time 35 with assurance that at all times, the color intensities of the paints therein do not vary.

The invention further contemplates the provision of mechanism employing pre-settable means for determining the proportion of paint 40 desired in relation to a quart; that is, should the formula call for eighteen ounces of one standard color and fourteen ounces of another, and only ten ounces of mixed paint being desired, said pre-settable means would be employed 45 to set the mechanism to dispense the proper quantities of standard paint.

50 Other features of the invention will later become apparent from the following description and the accompanying drawings, in which,

55 Fig. 1 is a front elevational view of a device

constructed in accordance with the invention, portions being broken away.

Fig. 2 is an enlarged elevational view showing the front mechanism of the device.

Fig. 3 is a vertical sectional view as taken 5 along the line 3—3 of Fig. 2.

Fig. 4 is a fragmentary elevational view as viewed in the direction of the arrow 4 of Fig. 3.

Fig. 5 is a further enlarged cross-sectional view as taken along the lines 5—5 of Fig. 3. 10

Fig. 6 is a vertical sectional view of a paint container holder employed in this invention.

The device as here disclosed comprises a frame 10 supported by brackets 11 on a base plate 12, the front of the frame being provided with a 15 front plate 13. It is also preferred to incorporate a compartment 14 symmetrically arranged in relation to the frame 10, the purposes of which will be later described. A paint container holder 15 (Fig. 6) is provided with an internally threaded seat 15 for the reception of the threaded end 17 of a paint container 18. These containers are usually in the form of round metal cans and have a capacity of one quart.

20 The holder 15 is preferably provided with a base 19 to insure stability and the bottom of the seat 16 is provided with a check valve 20 controlling the passage 21 in the holder.

25 Preferably integrally formed with the holder, there is provided a vertically disposed cylinder 30 22 having communications with the outer end of the passage 21. The cylinder is equipped with a piston 23 and provided with a stuffing box 24 at the upper end.

The upper end of the piston 23 is preferably 35 formed with an under-cut portion 25 and a stop pin 26 carried by the cylinder limits the downward movement of the piston in said cylinder. The lower open end of said cylinder is provided with a fitting 27 in which is incorporated a downwardly opening check valve 28.

40 Carried by the holder and in a manner so that it will enter the container 18, there is provided a pipe or tube 29 having at its upper end an air release valve 30 and carrying at intermediate portions, the vanes or mixing blades 31.

45 In use, a can of standard paint, after removal of its cover, is threaded into the seat 16, the holder 15 being inverted until the can is firmly seated. In order to thoroughly mix the paint 50 in the container, this whole assembly is thoroughly shaken, the vanes 31 serving to accomplish this. It is apparent that when the piston 23 is raised, paint from the container will 55 pass by the valve 20 through the passage 21.

into a cylinder 22, and when the piston is lowered, the paint in the cylinder will be ejected through the check valve 28. The stroke of the piston 23, therefore, determines the amount of paint drawn from the container. In the present instance, the cylinder 22 is designed to hold one ounce of paint when the piston has been raised the maximum amount and, therefore, each full stroke of the piston would discharge one ounce of paint through the valve 28. As the stroke is shortened, a lesser amount of paint is so discharged.

As paint is so withdrawn from the container, air is automatically drawn into said container through the tube 29 and valve 30. This air, being above the paint and trapped in the container, cannot escape and thus dehydration of the paint is obviated.

The holder above described is positioned in the frame 18 as best shown in Figs. 1, 2 and 3 and is supported on the base 12 thereof. In order to retain the holder against inadvertent displacement, there is provided means such as clamps 32 which engage the flange 19 of the holder. These clamps may be raised and lowered by manipulation of a handle 33 on one end of a shaft 34. The shaft, as here disclosed, is provided with a pair of eccentric portions 35 which are each engaged by an arm 36 pivotally mounted on the rod 37.

A spring such as shown at 38 is employed to maintain cooperative relation between each eccentric 35 and its respective arm 36. One end of the shaft 34 is preferably provided with a spirally wound spring 39, always tending to retain the eccentrics 35 so that they will act on the levers 36 to force the clamps 32 down on the flange 19 of the holder 15. Manipulation of the handle 33 counteracts the tension of the spring 39 to free the holder so that it may be removed from the frame.

In the upper portion of the frame 10, there is horizontally disposed a shaft 40 mounted in bearings 41 and provided with a handle 42. At a medial point of the frame 10, as viewed from the front, the shaft is provided with a worm 43 and on each side thereof is provided a spur pinion 44.

A frame 45 having respective rack portions 46 meshing with each pinion 44 is mounted for vertical movement in guide ways 47. The lower end of the frame 45 carries a pivoted latch 48, spring tensioned as at 49, and provided with a cam portion 50. This latch portion is also preferably provided with an upper extension finger 51. Oppositely disposed to the latch 48 is a somewhat similar pivoted latch 52, also formed with a cam 53, and spring-tensioned as at 49. The upper portion of the latch 52 is formed with an extension portion 53 over-standing the finger 51 of the latch 48. The latch 52 is also provided with a portion 54 engaged with the lower end of the link 55 pivoted at 56 to a rock member 57 pivotally mounted on the frame 10 as at 58. The rock member 57 is also formed with a horizontally disposed finger 59.

As viewed from the front, there is provided between the racks 46, a ratchet wheel 60 mounted for rotation at 61 and having fixed thereto a dog 62 engageable with the finger 59 of the rock member 57. The frame 45 is provided with a ratchet actuating pawl 63, and means such as the holding pawl 64 may be employed to retain the ratchet wheel 60 against inadvertent rotation.

The pivot shaft 61 of the ratchet wheel 60 is

provided, on the outside of the frame 10, with a knob 65 and a pointer 66 associated with the "stroke" scale 67.

In the operation of the machine, the holder 15 with a can of standard paint 18 is positioned and clamped in the frame 10 as shown and previously described and the pointer 66 is moved to that graduation of the scale 67 which is numbered for the number of strokes of the piston 23 desired. It is apparent that the dog 62 will then be radially spaced from the finger 59 in accordance with the setting of the pointer. As the handle 42 is turned to raise the frame 45, the latches 48 and 52, each engaged in the undercut 25 of the piston 23, will raise said piston in its cylinder 22 and in this way draw paint from the can 18 into the cylinder. Reverse rotation of the handle 42 will lower the frame 45 which pushes against the top of the piston, forcing it down in the cylinder, ejecting the paint in the piston through the valve 28. At the end of the stroke of the frame 45, the pawl 63 engages the ratchet wheel 60 to rotate it one tooth in a clockwise direction, thereby radially moving the dog 62 and the pointer 66 a like amount towards zero on the scale 67.

Continued rotation and reverse rotation of the handle 42 will eventually bring the dog 62 to the position shown in Fig. 2, at which time the pointer 66 will be at the graduation marked "1" on the scale 67. It will be noted that each time the frame 45 moves up, the latches 48 and 52 retain their hold on the piston but upon the last stroke subsequent to the one which placed the parts as shown in Fig. 2, the dog 62 will engage the finger 59 of the rock member 57 to rock said member in a counter-clockwise direction, pulling on the link 55 to rock the latch 52 away from the undercut 25. This rocking of the latch 52 causes the over-standing arm 53 to depress the finger 51 and thereby rocking the latch 48 outwardly also. Now, as the frame 45 moves upwardly, the latches 48 and 52 being out of engagement with the piston, said piston will not move upwardly. At this time, the operator has completed the dispensing of a desired quantity of paint, from the container 18, and hence the pointer 66 will be at "0".

The foregoing description relates to the dispensing mechanism. Now will be described the mechanism for controlling the length of stroke of the piston 23 which determines the amount of paint discharged through the valve 28 at each stroke.

A preferred manner of accomplishment is here illustrated, particularly in Figs. 1 to 5.

A worm wheel 70 on the sleeve 71 is arranged to mesh with the worm 43 and is disposed thereabove. The sleeve 71 is mounted for rotation in the frame 10 as at 72 and is provided at one end with an enlarged hub 73 carrying a pin 74. The outer end of the sleeve, outside of the frame 10, is provided with a pointer 75.

Disposed in the hollow of the sleeve 71, there is provided a shaft 76, one end projecting beyond the outer end of the sleeve 71 and having a hand knob 77 and an index pointer 78. The inner end of said shaft 76 is provided with an enlarged portion 79 which carries an abutment member 80 operatively engageable by the pin 74.

The outermost end of the portion 79 is arranged to protrude outside of the rear of the frame 10 and is flanged as at 81. This flange 81 is flanked on one side by a stationary plate 82 and on the other, by a plate 83 movable in relation to the plate 82. The plate 83 is mounted on studs 84 movable in the frame 10 and a com-

pression spring 85 on each stud serves to hold the plate 83 against the flange 81 of the shaft 76, the flange 81 in turn being pressed in this manner against the fixed plate 82.

5 The pressure of the plate 83 on the flange 81 may be relieved by manipulation of the handle 86 on the shaft 87 which is mounted in brackets 88 on the frame 10.

10 The shaft 87 is provided with a bail-like portion 89 which acts against the adjacent ends of levers 90, each pivoted at 91 on the plate 83. The other end of each of the levers 90 is arranged to contact the plate 82 as at 92.

15 In this manner (Fig. 3), movement of the handle 86 toward the right will rock the levers 90 around their pivots and with the points 92 acting as fulcrums, the plate 83 will be moved outwardly against the action of the springs 85. This frees the flange 81 and permits manual 20 rotation of the shaft 76 by means of the knob 77.

25 The pointer 75 and the index pointer 78 are associated with a scale 93, preferably graduated into thirty-two equal main divisions and such other equal minor subdivisions, preferably sixteen. This scale is based on the number of fluid ounces in a quart and the pointers associated therewith are employed in the following manner.

30 To best set forth the operation of the device, an example of one manner of using it will be described. First, the formulae are consulted and it is determined which two, three or more standard colors are necessary to attain the mixed color desired. For example, "Bordeaux" maroon requires 13½ fluid ounces of dark maroon, 18¼ fluid ounces of light maroon and ¼ ounce of black. The operator removes from the compartment 14, a can containing dark maroon paint 35 and its holder and places it into the machine as heretofore described. Since 13½ fluid ounces are called for in the formula, the index pointer 78 is set at "13½" on the scale 93. This is accomplished by a forward pull on the handle 86 to free the flange 81 and manipulation of the hand knob 97. The handle 86 is then released and the plates 82 and 83 will clamp the flange 81 to maintain the index pointer 78 where set. It will be noted that the abutment 80 which is related to the index pointer 78 will assume a definite spaced relative radial position to the pin 74.

40 As the handle 42 is rotated, the worm 43 will rotate the worm wheel 70 until the pin 74 strikes against the abutment 80. Since the frame 41 moves upward at the stroke of the handle 42, said frame will come to rest at this upper point when the pin 74 engages the abutment.

45 Reverse rotation of the handle 42 will move the frame down as previously described. It is apparent, therefore, that the stroke of the piston 23 has that relation to a full ounce as "13½" has to "32".

50 As previously described, the pointer 66 is set in relation to the stroke scale 67 at that graduation which corresponds to the number of ounces of mixed paint desired and, therefore, with the pointer 66 set at 12 as shown, twelve strokes of the piston will be made with each stroke dispensing from the paint container

13.5

32

55 of an ounce. Since the abutting action of the pin 74 against the abutment 80 serves as the

upper limit of the stroke of the piston and the lower limit of said stroke is determined by the pin 26 in the holder 15, the pointer 75 may be dispensed with but its employment in this device is advantageous since the operator can more flexibly utilize the mechanism with its aid.

60 After dispensing this amount of dark maroon, the holder and can of this paint are removed from the device and replaced in the compartment 14. A similar holder with a can of light maroon is then placed in the machine. Inasmuch as the formula calls for 18¼ fluid ounces of this color per quart of mixed paint, the index pointer 78 is now set at "18¼" on the scale 93 and the machine is operated as heretofore, twelve 15 strokes being made, each stroke dispensing

18.25

32

65 of an ounce. This holder is now removed from the device and a holder carrying a can of black paint is inserted and the index pointer 78 is set at "¼" on the scale 93 and the twelve strokes repeated, each stroke dispensing

25

32

70 of an ounce of black paint.

75 The container C which is placed below the orifice of the valve 28 will now contain twelve fluid ounces of paint comprising the three colors, dark maroon, light maroon and black in their proper proportions. It is now certain that this mixture of paints is the desired "Bordeaux" maroon sought to attain.

80 The scale 93, of course, is designed to suit the formulae used. Should other formulae such as one based on a hundred ounces, be employed, this scale would naturally be proportioned to suit.

85 From the foregoing, it is apparent that simple mechanism for the purpose intended has been provided and since it is apparent that many immaterial changes in the design, form, proportion and sizes of the parts may well be made 45 without departing from the general scope of the invention, the appended claims should not be read in the light of this specific disclosure but rather, in view of the prior art.

90 I claim:

95 1. A machine for mixing a predetermined quantity of paint comprising a removable paint holder, a paint receiving chamber associated therewith, reciprocatory means for withdrawing paint from said holder into the receiving chamber and for discharging the paint from said chamber into a collecting container, means for controlling the amount of paint so withdrawn and so discharged comprising means for indicating the number of strokes of said reciprocatory means to correspond to the number of measuring units in the total quantity of mixed paint desired, means for indicating and predetermining the length of each stroke of said reciprocatory means and thereby to predetermine the fractional part of said total amount withdrawn at each stroke in accordance with the ratio of the quantity of the paint of one color withdrawn from the container to the total quantity of mixed paint, and means for rendering inoperative the reciprocatory means upon removal of the predetermined proportioned quantity of paint from said holder.

100 2. A machine for mixing a predetermined quantity of paint comprising a holder for paint

75

- of a standard color, reciprocatory means for withdrawing paint from said holder, and presettable means operatively connected to the reciprocatory means to render said reciprocatory means inoperative after the required amount of the standard color has been withdrawn, said presettable means comprising presettable mechanism for predetermining the number of operative paint withdrawing strokes of the reciprocatory means and a second presettable mechanism for predetermining the operative length of each of said strokes, said second presettable mechanism including a scale for indicating the amount of said standard color in a formula for the paint to be mixed, a pointer, and means controlled by the pointer for regulating said strokes.
3. A machine for mixing paint of a number of standard colors to produce a predetermined quantity of mixed paint in which the standard colors are proportioned according to the proportions thereof in a predetermined formula, comprising reciprocatory means for dispensing paint of the standard color, revolute operating means for the reciprocatory means, means for rendering the reciprocatory means inoperative to dispense said standard color paint after a predetermined number of strokes of said reciprocatory means, and means for varying the length of said strokes independently of said second-mentioned means comprising a movable stop adapted to be arranged in the path of said revolute means.
4. A machine for mixing a predetermined quantity of paint comprising a paint holder, a paint-receiving cylinder in said holder, a piston reciprocably operable in said cylinder, means to operate said piston for withdrawing a proportioned quantity of paint from said container into the cylinder and for discharging the paint from said cylinder into a collecting container, and means for predetermining the quantity of paint so withdrawn and discharged, comprising stop means adapted to be arranged in the path of the piston operating means to determine the stroke of the piston, presettable indicating means operatively connected to the stop means, and means for predetermining the number of strokes of the piston including means for disengaging the operating means from the piston after the predetermined number of strokes have been made, and presettable indicating means for controlling the operation of the disengaging means.
5. A machine for mixing paint of a predetermined quantity and color comprising a paint holder for paint of a different color, a paint-receiving cylinder in said holder, a piston reciprocably operable in said cylinder, means to operate said piston for drawing a proportioned quantity of paint from said container into the cylinder and for discharging the paint from said cylinder into a collecting container, a scale provided with indicia indicating the proportionate quantities of paint of said different color in formulae for paint of said predetermined color, a pointer for the scale, and stop means operatively connected to said pointer and settable in the path of said piston operating means on the setting of said pointer to control the length of the stroke of the piston, said stop means comprising a pair of parallel plates, a third revolute plate interposed between the pair of plates, means for clamping all of said plates together with the revolute plate in any selected angular position, a relatively fixed stop member movable with the revolute plate, a relatively revolute stop mem-

ber adapted to engage the relatively fixed stop member to halt operation of said piston operating means, and means operatively connecting the revolute stop member to the piston operating means.

6. In a machine for mixing paint of a predetermined quantity and color, reciprocatory means for withdrawing paint from a container and for discharging said paint into a receiving vessel, and means for controlling the number of strokes of said reciprocatory means comprising a scale, a presettable pointer for the scale, a movable member controlled by the pointer for rendering the reciprocatory means inoperative, a ratchet wheel operatively connected to the pointer and to said member, and a pawl for the ratchet wheel mounted on the reciprocatory means and rotating said wheel, said member and said pointer a predetermined amount for each stroke of the reciprocatory means.

7. In a machine for mixing a predetermined quantity of paint, a pre-settable abutment, an index pointer, a scale associated with said abutment and said index pointer, and reciprocatory means for dispensing a proportioned quantity of paint from a container including a cylinder, a piston in the cylinder, a pin engageable with said abutment at the top of the stroke of the piston, a pointer associated with the mentioned scale and with the pin, a fixed abutment engageable with the piston at the bottom of its stroke, and means for rendering inoperative said piston upon the final stroke of the reciprocatory means.

8. In a device of the character described, a piston, a reciprocatory frame, means on the frame for engaging the piston for operation thereof, means for regulating the number of strokes of said piston, and means for disengaging the piston engaging means upon the last reciprocation of said frame.

9. In a machine for dispensing a predetermined quantity of paint of a standard color in accordance with the amount of paint of said standard color in a formula based on a unit quantity of mixed paint of which said standard color is an ingredient, a first indicating scale for the total quantity desired of the mixed paint of which the standard color dispensed by the machine is an ingredient, a second indicating scale for the amount of the standard color in said formula, means for withdrawing paint of the standard color from a container of such paint, pointers for each of said scales, and stop means operatively connected to said pointers and controlling the operation of said withdrawing means, said stop means rendering the withdrawing means inoperative after the predetermined quantity of said standard color has been dispensed by said withdrawing means.

10. In a machine for mixing a predetermined quantity of paint of a predetermined color, means including a movable pointer and a scale for indicating said predetermined quantity, means including a valved container for paint of a color other than the predetermined color for delivering a quantity of paint of said other color, said last mentioned delivered quantity being proportionally related to said predetermined quantity, a second movable pointer, a second scale associated with the second pointer and indicating the proportional relation of the delivered quantity to said predetermined quantity as given by a formula for any unit quantity of mixed paint, and adjustable stop means operatively connected to and settable with said second pointer.

11. In a machine for mixing a predetermined quantity of paint of a predetermined color, means for removably holding a selected one of a series of paint containers each containing paint of a different color or shade, means for withdrawing from each selected container a quantity of paint proportionally related to the amount of mixed paint desired, said means comprising reciprocatory means, means for regulating the stroke thereof, including a scale, a pointer for the scale, stop means controlled by the pointer and limiting the operative stroke of the reciprocatory means, means for removably locking the pointer and the stop means in a selected position relatively to the scale, a second pointer, and means operatively connected to and responsive to the setting of said second pointer for determining the number of operative strokes of said reciprocatory means.
12. In a machine for mixing a predetermined quantity of paint of a predetermined color, means for removably holding a selected one of a series of paint containers each containing paint of a different color or shade, means for withdrawing from each selected container a quantity of paint proportionally related to the amount of mixed paint desired, said means comprising reciprocatory means, means for regulating the stroke thereof, and means for rendering inoperative said reciprocatory means upon the last stroke thereof.
13. In a machine for dispensing a predetermined quantity of paint of a predetermined color, a paint container, a holder for the container, means for removably clamping the container to the holder, a pump carried by the holder, means for operating said pump, and means for rendering the pump inoperative after the predetermined quantity has been dispensed by the machine, comprising indicating means adapted to be set into a selected position to indicate said predetermined quantity and to also indicate the amount of the paint of said predetermined color in a formula for mixed paint of a desired color, and stop means operatively connected to the indicating means and adapted to be set into a selected position on the setting of the indicating means for rendering the pump inoperative.
14. In a machine for mixing a predetermined quantity of paint of a predetermined color, a container for paint of a different color, reciprocating means having a variable stroke for withdrawing paint from said container, indicating means for indicating said predetermined quantity and means for also indicating the amount of paint of said different color contained in a unit quantity of mixed paint of the predetermined color, stop means for controlling the effective number of paint withdrawing strokes of the reciprocating means, stop means for determining the length of each stroke, means operatively connecting the indicating means to the stop means, and valve means for controlling the flow of paint from the container, said valve means being opened and closed on the reciprocation of the reciprocating means.
15. In a paint dispensing machine, a scale, a rotatable pointer for said scale, a stop operatively connected to the pointer for rotation therewith, a plate rotatable with the pointer and with said stop, means for locking said plate to prevent operation of said pointer and thereby to set said stop, a pump, means for operating said pump, and means for controlling the operation of said pump comprising a rotatable pin adapted to en-
- gage said stop after a predetermined operation of said pump operating means.
16. In a machine for dispensing a predetermined total quantity of mixed paint, of a color other than standard, said total quantity comprising lesser quantities of a plurality of paints of standard colors, means including a valve for discharging a standard color paint from a selected container, a total quantity indicating scale, a movable pointer adapted to be set to indicate said total predetermined quantity on said scale, means adjustable by and operatively connected to said pointer to render the discharging means inoperative after the required quantity of standard paint has been discharged from the container, and means cooperating with said pointer, scale and adjusting means, for limiting the total quantity discharged from said container to the same proportion of standard paint as that given in a formula for said mixed paint, said last-mentioned means including a second indicating scale and a second movable pointer for said second scale adapted to be set to indicate the quantity of standard paint in the formula.
17. In a machine for delivering from different containers of standard-color paints a total predetermined quantity of mixed paint different in color from any of its standard-paint ingredients and in accordance with a formula for a unit quantity of said mixed paint, a reciprocating pump, means for operatively connecting the pump to a container of standard color paint including a valve opened on the stroke of the pump in one direction to remove paint from the container and a second valve opened on the opposite stroke of the pump to discharge the paint, indicating means for indicating said predetermined quantity and for also indicating the quantity of standard paint in said unit formula, and means controlled by the indicating means for controlling the length of the stroke of the pump and the number of effective strokes thereof and thereby causing delivery of that amount of standard paint equal to the product of the amount of said standard paint indicated by the indicating means, and the total predetermined quantity of mixed paint indicated by said indicating means.
18. In a machine for delivering from different containers of standard-color paints a total predetermined quantity of mixed paint different in color from any of its standard-paint ingredients and in accordance with a formula for a unit quantity of said mixed paint, a pump, a discharge valve for the container operated on operation of the pump, a second discharge valve in spaced relation to the container discharge valve and operated on operation of the pump to open when the first discharge valve is closed and to close when the first discharge valve is open, indicating means for indicating said predetermined quantity and the quantity of standard paint in said unit formula, and pump controlling means controlled by the indicating means to effect discharge through said second discharge valve of that amount of standard paint equal to the product of said predetermined quantity and the quantity of said standard paint indicated by the indicating means.
19. In a machine for delivering from different containers of standard-color paints a total predetermined quantity of mixed paint different in color from any of its standard-paint ingredients and in accordance with a formula for a unit quantity of said mixed paint, a reciprocating

pump, revoluble means including a manually rotatable handle for operating the pump, a first discharge valve for the container adapted to open on rotation of the handle in one direction, 5 a second discharge valve for discharging paint from the machine adapted to open on rotation of the handle in the opposite direction, and means for controlling the amount of angular rotation of the handle and the number of effective 10 rotations of the handle to predetermine the quantity of standard color paint withdrawn from the container and delivered by the machine.

20. In a machine of the character described, revoluble indicating means for indicating the 15 quantity of a standard-color-paint ingredient in a formula for a unit quantity of mixed paint comprising a pair of coaxially mounted revoluble pointers, a scale for said pointers, a relatively fixed stop movable with one of said pointers, means for clamping said stop in any angular position corresponding to the position of one of 20 said pointers relatively to the scale, said clamping means comprising a pair of plates, a third plate interposed between said pair, and a clamping 25 handle for clamping all of said plates together, a revoluble stop movable with the other of said pointers, and paint pumping means operatively connected to the revoluble stop and to 30 said other pointer and adapted to operate until said stops are brought into engagement and said pointers are coincident on the scale.

21. In a machine of the character described, a scale, a pointer for said scale, a relatively fixed stop member, a first plate, a pivotally supported 35 member carrying the pointer, stop member and plate, means for clamping said member in the position into which it is set on the movement of said pointer relatively to the scale, said means comprising a pair of clamping plates arranged at 40 opposite sides of the first plate, and means for clamping all of said plates together in the adjusted position of said first plate, a pump for delivering paint, a relatively movable stop member arranged to move in a path to engage the relatively fixed stop member, and means operatively 45 connecting the relatively movable stop member to the pump whereby the pump is rendered inoperative on the engagement of said stop members with each other.

50. 22. In a machine for delivering from different containers of standard color paints a total predetermined quantity of mixed color paint different in color from any of its standard-color ingredients and in accordance with a formula for 55 a given quantity of said mixed color paint, a container for paint of one standard color, a pump associated with the container and including a piston, means for removably supporting the container and pump whereby another similar container and pump may be substituted for said 60 first-mentioned container and pump, means for operating the pump, means adapted to be engaged with and disengaged from the piston for connecting the pump operating means to the 65 pump and for disconnecting the pump operating means from the pump, indicating means operatively connected to the pump operating means for indicating the proportionate amount of each standard color paint in the formula and for also 70 indicating said predetermined quantity, and means for controlling the amount of paint of the standard color discharged by the pump and for

limiting said amount to the product of the amount of said standard color paint in the formula and the fraction whose numerator is said predetermined quantity of mixed color paint desired and whose denominator is the total quantity of mixed paint in the formula. 8

23. In a machine for delivering from different containers of standard color paints a total predetermined quantity of mixed color paint different in color from any of its standard-color ingredients and in accordance with a formula for a given quantity of said mixed color paint, a piston for and associated with each of the containers, means connectible to and disconnectible from the piston of any selected container for operating the piston to withdraw paint of a standard color from the selected container, means for indicating the total quantity desired of the mixed paint of which the standard color paint dispensed by the machine is an ingredient, a second 10 indicating means for indicating the proportionate amount of the standard color paint in the formula, and means operatively connected to the indicating means and controlling the operation of the piston operating means. 15

24. In a machine for proportioning different standard color paints to produce a predetermined total quantity of paint of a mixed color, said quantity being different from that given by a formula for the mixed color paint, a chamber 30 for standard color paint, a valve for said chamber, a piston within and carried by the chamber, means for removably supporting the chamber in position for movement of the piston therein, means for moving the piston in one direction to discharge paint from the chamber and in the other direction to draw paint into the chamber, means for indicating said total quantity, means for indicating the quantity of standard color paint in the formula, means for operatively connecting the piston with said indicating means, and means for rendering the piston moving means inoperative to move the piston after the required quantity of standard color paint has been dispensed, said required quantity being 40 the product of the amount of said standard color paint in the formula and the fraction whose numerator is said predetermined quantity of mixed color paint and whose denominator is the total quantity of mixed color paint in the formula. 45

25. In a machine for proportioning different standard color paints to produce a predetermined total quantity of paint of a mixed color, said quantity being different from that given by a formula for the mixed color paint, a container for paint of one standard color, a pump associated with the container and including a piston, means for removably supporting the container and pump for the substitution of said container and pump by a similar container and pump for paint of a different standard color, a valve for the container, means for moving the piston to discharge paint from the container, indicating means to indicate said total quantity, additional indicating means to indicate the quantity given by said formula of that standard color paint in the container, and means for rendering the piston moving means inoperative after the required quantity of standard color paint has been 55 discharged from the container. 60
